DESIGN FOR A CUP

Karl Bayreuther, Selb, Germany, assignor to The Rosenthal China Corporation, New York, N. Y., a corporation of New York

Application December 29, 1936, Serial No. 66,794

Term of patent 14 years

To all whom it may concern:

Be it known that I, Karl Bayreuther, a citizen of Germany and a resident of Selb, Bavaria, Germany, have invented a new, original, and ornamental Design for a Cup, of which the following is a specification, reference being had to the accompanying drawing, forming part thereof, in which Fig. 1 is a perspective view of the cup, showing my new design; Fig. 2 is a top plan view; Fig. 3 is a bottom plan view, and Fig. 4 is a partial view in section.

I claim:

The ornamental design for a cup, as shown.

KARL BAYREUTHER.
